UNITED STATES PATENT OFFICE.

FRED S. CARR, OF NEWTON, MASSACHUSETTS, ASSIGNOR TO CARR FASTENER COMPANY, OF CAMBRIDGE, MASSACHUSETTS, A CORPORATION OF MAINE.

FASTENER.

Application filed March 8, 1921. Serial No. 450,744.

To all whom it may concern:

Be it known that I, FRED S. CARR, a citizen of the United States, and a resident of Newton, in the county of Middlesex and 5 Commonwealth of Massachusetts, have invented an Improvement in Fasteners, of which the following description, in connection with the accompanying drawings, is a specification, like characters on the drawings 10 representing like parts.

This invention pertains to improvements in separable fasteners. It is among the objects of the invention to provide a separable fastener of simple construction, great durability and of superior holding power.

In the drawings, which show a preferred form of one illustrative embodiment of my invention:—

Figure 1 is an elevation of two pieces of 20 fabric to which the stud and socket members of a preferred form of separable fastener are attached;

Fig. 2 is a section on the line 2—2 of Fig. 1;

Fig. 3 is a front elevation of the preferred 25 form of socket illustrated in Figs. 1 and 2;

Fig. 4 is an elevation of the preferred form of stud shown in Figs. 1 and 2; and

Fig. 5 is a section through the fastener on 30 the line 5—5 of Fig. 1.

Referring to the drawings and to the preferred form of my invention selected for 35 illustrative purposes, I have shown a stud including a head 6, a neck 7 and a base 8, and secured to the stud-carrying fabric 9 in any suitable way as by stitching 10. I have shown a cooperating socket including 40 a casing 11 providing a stud-receiving plate 12 having a stud-receiving aperture 13 therein and containing a spring 14 presenting two portions intersecting the stud-receiving aperture 13. The preferred form of 45 spring will be more fully described herein-after. The preferred form of socket illustrated is sewn to the socket-carrying fabric 15 by stitches 16. Where my invention is utilized in connection with fastening elements adapted to be sewn to their carrying fabrics, I prefer to make the casing 11 in

50 one piece and to provide for holding in the spring 14 by a flanged-over rim 17 of the casing. The stud-receiving aperture 13 is preferably notched at one side providing the recess 18 communicating with the stud-receiving aperture 13 and adapted to per-

mit the stud to shift laterally in the socket to a small extent, sufficient to prevent separation of stud and socket by the resolution of forces arising from lateral strain between stud and socket urging the stud toward the notch, or in the general direction of the notch, the notch, however, preferably being of such dimension relative to the neck and head of the stud that separation of stud and socket may be effected even while under considerable lateral strain by a convenient tipping movement at an angle somewhat greater than that likely to be produced by the resolution of forces arising from lateral strains in the direction indicated.

The spring 14, as before described, preferably intersects the stud-receiving aperture 13 at opposite sides thereof as at 19 and 20. Between these portions, the spring preferably forms a loop, the end of which extends 60 adjacent to the peripheral wall of the socket underlying the flange 17 at 21. At the other side of the stud-engaging portions 19, and 20 the spring underlies the flange 17 at 22 and 23 preferably, as illustrated, being provided with outwardly turned portions 24 and 25 spaced away from the wall of the casing through a substantial distance so as to increase the resiliency of the stud-engaging 65 portions of the spring.

The spring may, if desired, be positioned relative to its casing by a projection 31 extending within the loop of the spring adjacent its central portion 21. The loop in the spring between the stud-engaging portions 90 19 and 20 is preferably such as to provide inclined portions intersecting a part of the stud-receiving aperture 13 at the side opposite the notch 18 so that as the spring gripping the head of the stud tends to 95 move the stud-engaging portions 19 and 20 toward one another by reason of enlargement of the loop in the spring the inclined portions will tend to press the neck of the stud toward the notch 18.

When the head of the stud 6 is entered 100 through the stud-receiving aperture 13 in the casing, the stud-engaging spring jaws 19 and 20 are spread apart and grip the neck 7 of the stud when the latter is fully 105 entered in the socket. The notch 18 in the socket is preferably adjacent the edge 30 of the socket-carrying fabric 15, so that the normal lateral strain between stud and socket will lead the neck of the stud into 110

the notch 18. When the stud is entered in this notch, the resolution of forces arising from lateral strain will not cause the stud to tip in such a way as to become separated from the socket. On the other hand, when it is desired to separate the stud from the socket, a pull on either the stud or socket in either an axial direction or one producing a tip somewhat greater than that arising from the resolution of forces under lateral strain will cause the stud to be released from the socket even though a considerable amount of lateral strain between stud and socket exists at the time of separation.

While I have shown and described a preferred form of one embodiment of my invention, it will be understood that changes involving omission, substitution, alteration and reversal of parts, and even changes in the mode of operation, may be made without departing from the scope of my invention, which is best defined in the following claims.

25. Claims.

1. In a separable fastener, a socket comprising a casing having a plate with a stud-receiving aperture therethrough and a spring in said casing presenting two portions intersecting said aperture, said spring presenting a complete loop at one side of said aperture and expansion of said loop resiliently pressing said two portions toward one another to grip a stud entered in said aperture, the opposed spring portions at the other side of said loop uncrossed and lying generally in the same plane.

2. In a separable fastener, a socket comprising a casing having a plate with a stud-receiving aperture therethrough and a notch communicating with said aperture, a spring in said casing presenting two portions intersecting said aperture, said spring presenting a complete loop and expansion of said loop resiliently pressing said two portions toward one another to grip a stud

entered in said aperture; said portions angled to press the stud toward that end of the aperture away from said loop and into said notch.

3. A socket for separable fasteners, said socket comprising a casing having one side generally closed by a plate having a stud-receiving aperture therein and its other side generally open but partially closed by a flanged-over rim of said casing, and a spring in said casing providing two portions intersecting the aperture, said spring formed of a single piece of wire underlying said flange at three points and bearing 60 against the periphery of said casing at one of said points only.

4. A socket for separable fasteners, said socket comprising a casing having one side generally closed by a plate having a stud-receiving aperture therein and its other side generally open but partially closed by a flanged-over rim of said casing, and a spring in said casing providing two portions intersecting the aperture, said spring formed 70 of a single piece of wire underlying said flange at three points and bearing against the periphery of said casing at one of said points only, said spring presenting a complete loop adjacent said one point.

5. A socket for separable fasteners, said socket comprising a casing having one side generally closed by a plate having a stud-receiving aperture therein and its other side generally open but partially closed by a flanged-over rim of said casing, and a spring in said casing providing two portions intersecting the aperture, said spring formed of a single piece of wire underlying said flange at three points and bearing against the periphery of said casing at one of said points only, said spring held against rotation in said socket by a spring-retaining projection from said casing adjacent said one point.

In testimony whereof, I have signed my name to this specification.

FRED S. CARR.
